UNITED STATES PATENT OFFICE.

CHARLES F. WHALEY, OF ST. PAUL, MINNESOTA.

DESIGN FOR A BICYCLE-STIRRUP UPPER.

SPECIFICATION forming part of Design No. 30,667, dated May 2, 1899.

Application filed February 4, 1899. Serial No. 704,590. Term of patent 7 years.

To all whom it may concern:

Be it known that I, CHARLES F. WHALEY, a citizen of the United States, residing at St. Paul, in the county of Ramsey and State of Minnesota, have produced and invented a new and original Design for Bicycle-Stirrup Up-pers, of which the following is a specification.

This invention relates to the "uppers" of the stirrups used upon the pedals of bicycles to support the foot of the rider; and the design thereof is illustrated in the accompan-ying drawings, in which—

Figure 1 is a perspective view of the upper from the rear end, and Fig. 2 is a perspective 15 view of the upper from the front end. Fig. 3 is a bottom plan view of the upper.

The leading feature of my design is the out-line of the bicycle-stirrup upper in the form herein shown and described.

Referring to the drawings by letter, A' re-presents the main body portion, curved in its upper outline and smaller at its front end A² than at the rear end A³ and with the edges of

the sides turned inward, as at A⁴ A⁵. Em-bracing the rear outer edge of the body por-tion A' is a stay-band B', conforming to the curve and shape of the body portion and with its ends turned under the turned-under sides A⁴ A⁵ and fastened thereto, as by rivets. The bent-under ends of the stay-band are 30 formed with enlargements B² B³, as shown. The outlines of the band B' where the exten-sions or enlargements are united thereto are in curved lines, as shown at e' e².

Having thus described my invention, what 35 I claim as new, and desire to secure by Letters Patent, is—

The design for a bicycle-stirrup upper as herein shown and described.

In testimony whereof I have hereunto set 40 my hand in the presence of two subscribing witnesses.

CHARLES F. WHALEY.

In presence of—

LEWIS D. MANN,
C. N. WOODWARD.
